UNITED STATES PATENT OFFICE

95,393

DESIGN FOR A TOOL HANDLE OR SIMILAR ARTICLE

William F. Wise, Detroit, Mich.

Application December 19, 1934, Serial No. 54,504

Term of patent 7 years

To all whom it may concern:

Be it known that I, William F. Wise, a citizen of the United States, residing at Detroit, post office address 2550 Calvert Ave., in the county of Wayne and State of Michigan, have invented a new, original, and ornamental Design for a Tool Handle or Similar Article, of which the following is a specification, reference being had to the accompanying drawing, forming part thereof.

Figure 2 is a top plan view of the tool handle. The tool handle is used for holding a corkscrew, a knife, envelope opener, screw driver, or the like.

I claim:

The ornamental design for a tool handle or similar article, substantially as shown and described.

WILLIAM F. WISE.
